UNITED STATES PATENT OFFICE.

EMIL RICHARD, OF PITTSBURGH, PENNSYLVANIA.

PIN-FASTENER.

1,369,355.

Specification of Letters Patent. Patented Feb. 22, 1921.

Application filed April 2, 1920. Serial No. 370,690.

To all whom it may concern:

Be it known that I, EMIL RICHARD, a citizen of the United States of America, residing at Pittsburgh, in the county of Allegheny and State of Pennsylvania, have invented certain new and useful Improvements in Pin-Fasteners, of which the following is a specification.

This invention relates to certain new and useful improvements in pin fasteners and more particularly to that class of pin fasteners embodying an article of jewelry and including brooches, breast pins and the like.

The principal object of the present invention is to provide a very simple, positive and serviceable device of the character specified, which includes efficient means for holding against accidental detachment from a garment or other support upon which it is fastened.

In order to render the nature of the invention clear to persons skilled in the art to which it appertains, the invention will be described in its embodiment in an ordinary breast pin or brooch.

Reference is to be had to the accompanying drawing forming part of this specification in which similar characters of reference indicate corresponding parts in all of the figures.

Figure 1 is a rear elevational view of a brooch constructed in accordance with the present invention, the pin being shown partly broken away,

Fig. 2 is a side elevational view of the device shown in Fig. 1, the pin being indicated by dotted lines in open position,

Fig. 3 is an enlarged end elevational view looking toward the left of Fig. 1 and with the pin removed,

Fig. 4 is an enlarged transverse sectional view taken substantially upon line IV-IV of Fig. 1,

Fig. 5 is a view similar to Fig. 4 taken upon line V-V of Fig. 2,

Fig. 6 shows the pin in elevational and transverse sectional views,

Fig. 7 is a view similar to Fig. 6 of a modified form of the pin,

Fig. 8 is a view similar to Fig. 2 drawn on a smaller scale and showing a modification of the invention, and

Fig. 9 is a side view of the pin of the device shown in Fig. 8, removed.

Referring more in detail to the accompanying drawings, 5 denotes the body plate

which is shown as rectangular in form, but which, if desired, can be changed to any suitable shape without affecting the advantages gained through the use of the several parts of my invention. To the rear side of this plate and at the ends thereof are secured a sleeve and a seat 6 and 7 respectively. In the form of the invention shown in Figs. 1 to 5 inclusive, the seat 7 is provided with a spring catch 8, the purpose of which will be hereinafter set forth. 9 represents the pin having a head 10 at one end and pointed at its other end, a perforation or eye 11 being provided transversely in the pointed end of the pin for reception of the spring catch 8.

The sleeve 6 is hinged as at 12 for swinging movement relative to the plate 5 whereby the pin may be swung outwardly from the full line position of Fig. 2 to the dotted line position thereof for convenience in attaching and detaching the device.

The pin 9 is slid through the sleeve 6 longitudinally so as to allow the pointed end of the pin to be inserted in the seat 7 or removed from the latter, and in order to prevent rotation of the pin for insuring proper alinement of the catch 8 and eye 11, the sleeve 6 is provided with inwardly extending keys or lugs 13 which fit into the longitudinal side grooves 14 that are provided in the pin 9. The head 10 eliminates inward movement of the pin 9 wherein the eye 11 of the latter is positioned to receive the catch 8. In order to effectively guide the pointed end of the pin into the seat 7, the latter may be cut away or notched at its inner end as at 15.

In the preferred form of the invention, the seat 7 is of tubular form and is provided with a rigid stud 16 which is detachably connected to the plate 5 by any suitable means so as to make the seat renewable if broken. As shown, the stud 16 is threaded into a socket 17 formed on the plate 5 for accomplishing this result.

The spring catch 8 preferably resides in a pin which is normally pressed inwardly to latching position by means of a helical spring 18 that encircles the pin within a sleeve or hollow stud 19 that is rigid with and projects laterally from the seat 7 at one side, the spring 18 bearing at its inner end upon a washer or the like 20 which is fastened upon the pin, and at its outer end upon the inwardly directed annular flange 21 which

is formed upon the outer end of the tubular stud 19. A sleeve 22 is slidably disposed upon the tubular stud 19 and centrally connected to the outer end of the pin 8 by flanging the latter as at 23 so that the sleeve 22 may be grasped and pulled outwardly for withdrawing the catch pin from the eye 11.

The sleeve 6 is preferably provided with an ear 24 which is received between a pair of ears 25 carried by the plate 5 for providing pivotal connection 12 as before mentioned.

Although, for the purpose of strength and durability, the sleeve 6 is provided with a pair of keys 13 and the pin 9 is provided with a pair of corresponding grooves 14 as shown in Figs. 1, 2, 3, 5 and 6, it will be sufficient, if desired, to provide merely one key 13 and only providing the pin 9 with one groove 14' as shown in Fig. 7.

As shown in Figs. 8 and 9, the sleeve 6 may be provided with a circular bore and internally threaded for threaded reception 25 of the portion of the pin 9 indicated at 26 adjacent the head 10. When this is done the spring catch may be limited and the pin 9 is effectively held with its point within the seat 7'. In Fig. 8 the seat 7' is shown 30 of cone-shape and provided with a threaded stud 16' detachably screwed into a socket provided in the body plate 5'. The sleeve 6 of Fig. 8 is also pivoted as at 12 to the body plate and may be detachably connected as 35 at 27 with said plate in a manner similar to the connection of the stud 16' therewith.

It will be seen that when my invention is secured to laces and analogous fabrics, the point of the pin will be seated in and 40 protected by the seat, and the fastening pin *per se* is securely held in position.

When it is desired to detach my device from the fabric, the spring catch is pulled outwardly to release the pin 9 and this pin 45 is then drawn through the sleeve 6 sufficiently to permit the pin and sleeve to swing for opening the device. With the construction of Figs. 8 and 9, it is merely necessary to impart a slight rotation to the pin 9 until 50 the threaded portion 26 thereof is disengaged from the threaded interior of the sleeve 6, whereupon the pin 9 may then be withdrawn through the sleeve 6 sufficiently to permit the pin 9 to move out of the seat 55 7'. The pin 9 may then be swung outwardly in the usual manner.

From the foregoing description, taken in

connection with the accompanying drawing, the operation and advantages of my invention will be readily understood.

Minor changes may be made without departing from the spirit and scope of the invention as claimed.

What I claim as new is:

1. The combination with a body plate 65 having at one end a pivoted sleeve and at the other end a seat, of a pin longitudinally slidable through said sleeve and adapted for reception by said seat at its pointed end, means for retaining the pin against movement through the sleeve for retaining the pointed end of the pin in said seat, the pointed end portion of said pin being provided with an eye, and said last named means including a spring pressed catch normally projected into said eye.

2. The combination with a body plate having at one end a pivoted sleeve and at the other end a seat, of a pin longitudinally slidable through said sleeve and adapted for 80 reception by said seat at its pointed end, means for retaining the pin against movement through the sleeve for retaining the pointed end of the pin in said seat, the pointed end portion of said pin being provided with an eye, said last named means including a spring pressed catch normally projected into said eye, and means to retain the pin against axial rotation relative to the sleeve for insuring registration of the 85 eye of the pin with said catch.

3. The combination with a body plate having at one end a sleeve and at the other end a seat, of a pin longitudinally slidable through said sleeve with its pointed end 95 adapted for reception by said seat, and means including a screw threaded stud rigid with said seat detachably connecting said seat to said body plate.

4. In a pin fastener of the class described, 100 a tubular seat having a hollow stud projecting laterally from one side thereof and rigid therewith, the outer end of said stud being inwardly flanged, a pin slidably carried by said seat and arranged transversely of the 105 latter with its inner end projecting into the bore of said seat, a spring encircling said pin within said hollow stud for normally pressing said pin inwardly relative to the seat, and a member attached to said pin 110 adapted to be grasped for withdrawing the latter from the bore of said seat.

In testimony whereof I affix my signature.

EMIL RICHARD.
